CLAIM

The ornamental design for an amphibian aeroplane, as shown and described.

DESCRIPTION

FIG. 1 is a perspective view of an amphibian aeroplane; FIG. 2 is a front view thereof; FIG. 3 is a top view thereof; FIG. 4 is a left-side view thereof, the right-side view being a mirror image of the left-side view; FIG. 5 is bottom view thereof; FIG. 6 is another perspective view thereof with the wings in a folded configuration; and, FIG. 7 is another perspective view thereof with the canopy open and the landing gear extended. The broken lines depict environmental subject matter only and form no part of the claimed design.
